UNITED STATES PATENT OFFICE.

RUBEN CASPAR, OF ATTLEBOROUGH, MASSACHUSETTS.

DESIGN FOR A CUFF-HOLDER.

SPECIFICATION forming part of Design No. 28,972, dated July 5, 1898.

Application filed June 8, 1898. Serial No. 682,953. Term of patent 14 years.

To all whom it may concern:

Be it known that I, RUBEN CASPAR, a citizen of the United States, residing at Attleborough, in the county of Bristol and State of Massachusetts, have invented and produced a new and original Design for a Cuff-Holder, of which the following is a specification, reference being had to the accompanying drawings, forming part thereof.

10 Figure 1 is a front view of a cuff-holder, showing my design. Fig. 2 is a side view, and Fig. 3 a transverse sectional view, of the same.

15 The leading feature of my design consists in the ornamentation of the bar connecting the clamp with the button.

20 In the drawings, *a* indicates the bar; *b*, a shoe-shaped spring-clamp terminating in the bent toes *b' b'* at one end and the semicircular heel *b²* at the other end. The shoe-shaped clamp extends transversely to the bar *a*; *c*, a button connected to the post *c'*, which ex-

tends from the end of the bar *a* opposite to the end from which the shoe-shaped clamp extends. The bar *a* is ornamented with the 25 raised scrolls 1 1, extending from one end along the curved margins of the bar, the raised bead ornaments 2 2, extending along the margin of the central portion of the bar *a*, the scrolls 3 3, and the crossed stems 4 4, 30 terminating at the ends into scrolls, the whole ornamentation inclosing the long panel 5.

Having thus described my invention, what I claim as new, and desire to secure by Letters Patent, is—

35 The design for a cuff-holder substantially as herein shown and described.

In witness whereof I have hereunto set my hand.

RUBEN CASPAR.
